Attorney.

UNITED STATES PATENT OFFICE.

WILLIAM REDFORD MULOCK, OF WINNIPEG, MANITOBA, CANADA.

NOISE-REDUCING TYPEWRITER-PLATEN.

1,382,218.

Specification of Letters Patent. Patented June 21, 1921.

Application filed December 15, 1920. Serial No. 431,014.

To all whom it may concern:

Be it known that I, WILLIAM REDFORD MULOCK, a subject of the King of Great Britain, and resident of Winnipeg, in the 5 Province of Manitoba, Dominion of Canada, have invented certain new and useful Improvements in Noise-Reducing Typewriter-Platens, of which the following is a full, clear, and exact specification.

10 This invention relates to platens for typewriting machines, and has for its object to provide an improved form of platen which may be substituted for that now in general use and which will greatly reduce the noise 15 caused by the type striking the platens now in common use.

The present invention contemplates the use of a non-rotating skeleton cylindrical platen frame provided with a cushioned 20 striking or platen strip which does not revolve, and a plurality of paper-feeding rollers in the platen adapted to be simultaneously rotated for moving the paper over said striking strip and between it and the ribbon. 25 The skeleton platen, carrying the striking strip and paper-feeding rollers, is to be reciprocated as and interchangeable with the ordinary platen on the carriage of a typewriting machine but will be secured so as 30 not to rotate.

The invention will be first hereinafter described in connection with the accompanying drawings, which constitute part of this specification, and then more specifically defined in 35 the claims at the end of the description.

In the accompanying drawings, wherein similar reference characters are used to designate corresponding parts throughout the several views:—

40 Figure 1 is a plan view of a platen constructed substantially in accordance with this invention.

Fig. 2 is central longitudinal section thereof.

45 Fig. 3 is a cross section on the line III—III of Fig. 2 showing a part of a typewriter carriage in dotted lines.

Fig. 4 is a section on the line IV—IV of Fig. 2.

50 Fig. 5 is a detailed sectional view of the cushioned striking strip showing more

clearly how it is maintained in proper alignment.

Fig. 6 is a front elevation of the right hand end portion of the casing showing the 55 screw pins 3, 3, and the bar of the carriage engaged thereby, said bar and the carriage being shown in dotted lines.

The carriage of a typewriting machine is indicated in a general way in dotted lines at 60 1 in Fig. 3 of the drawings, and my improved platen is supported thereon in the same manner as the ordinary roller platen, but is secured against rotation in any suitable manner, as by the pair of screw pins 3 65 at each end arranged at opposite sides of a fixed bar 4 of the carriage 1, as is more clearly seen in Fig. 6. The platen may be of any ordinary or desired length, as indicated by breaking away its middle portion 70 in Figs. 1 and 2.

The platen frame may have end disks 5 which fit inside of the ends of the skeleton casing 6 and to which they are fastened. A central shaft 7 extends rotatably through the 75 centers of the end disks and has milled caps 8 on its opposite ends for turning said shaft by hand. The area of the skeleton casing 6 is reduced as much as possible in order that there may be less material in it to produce 80 sound from the striking of the type. Said casing has a slot 8a extending horizontally substantially from end to end thereof in its front portion. In this slot there is arranged a striking or platen strip 9 which substantially fills said slot and is maintained in 85 proper alignment therein in any suitable manner, preferably by a rubber strip 24 (as in Fig. 5) along the casing on the lower edge of the said slot on which it will rest. The 90 strip 9 may be of rubber or any other suitable material, and it is preferably set in a clip 10 and cushioned on springs 11 supported on a sleeve 12 loosely mounted on the center shaft 7, as best shown in Fig. 5, but 95 any other means for cushioning the strip 9 may be employed without affecting the principle of this invention.

Journalized in the end disks 5 of the platen are a plurality of paper-feeding rollers 13 100 of any necessary or desirable length and diameter. Three such rollers are illustrated,

one being arranged at the back of the platen and the other two above and below the platen strip 9, respectively, but the number and positions of these paper-feeding rollers 5 may be changed if desired to suit different kinds of typewriting machines. Each roller 13 preferably has its paper-engaging surface made of rubber 14 and arranged to project slightly beyond the surface of the platen 10 casing so as to engage the paper 15, Fig. 3, and carry it around the platen between the striking strip and the ribbon which is indicated at 22 in said figure. When the platen is in use on the carriage of a typewriting machine, the paper-holding rollers 16 of said carriage will press the paper into frictional contact with the platen rollers, 13, as indicated in dotted lines in Fig. 3.

The rollers 13 extend through the right hand end disk 5 of the platen and have gears 17 fixed thereon to mesh with an internal gear 18 on the inner face of an end member 19 which is fast on the center shaft 7 and also has the usual ratchet teeth 20 on its periphery for engagement with the pawl (not shown) which is ordinarily provided on a typewriting machine for mechanically regulating the feeding of the paper during the operation of the machine. By means of this 20 construction, the rotation of the center shaft by said pawl or by the hands of the operator grasping one or both of the milled caps 8 will simultaneously revolve all of the rollers 13 so as to feed the paper 15, Fig. 3, around the platen and across the striking or platen strip 9.

One or more bars may be used along the top of the platen between the end disks 5 to hold said platen rigid where the skeleton 40 casing 6 is cut away. This bar will be just above the roller which is above the narrow strip of the casing which forms the upper edge of the slot 8^a and it will take the paper as it comes off the roller. Rubber washers 45 and insulating strips (not shown) are used where possible in the construction of the platen with a view to eliminating noise.

By making the platen-frame in skeleton form and reducing the striking surface to a 50 narrow cushioned strip the noise usually incident to the type striking the common hard roller platen is very greatly reduced, and the provision of the simultaneously actuated paper-feeding rollers insures the 55 even and true movement of the paper during the operation of a typewriting machine equipped with the present invention. It will be understood that details of construction may be altered without departing from the spirit or sacrificing the advantages of the invention.

Having thus described my invention, what I claim as new and desire to secure by Letters Patent of the United States is:

65 1. In a typewriter platen frame, the com-

bination with a cushioned striking or platen strip secured against rotation, of a plurality of paper-feeding rollers mounted within said platen frame and arranged at intervals around its periphery for moving a sheet 70 of paper across said striking or platen strip, and means for simultaneously actuating said rollers.

2. In a typewriter platen, the combination with a skeleton cylindrical platen frame 75 secured against rotation and having a longitudinal space therein, of a striking or platen strip arranged in said space and cushioned to yield under the impact of the type, and coöperating paper-feeding rollers mounted 80 in the platen frame to coöperate with the paper-feeding rollers of a typewriter carriage outside the periphery of said platen frame.

3. In a typewriter platen, the combination with a skeleton cylindrical platen frame secured against rotation and having an open longitudinal space therein, of a cushioned striking or platen strip arranged in said space, coöperating with paper-feeding rollers 90 mounted in the platen frame, and means for simultaneously actuating all of said rollers.

4. In a typewriter platen, the combination with a skeleton cylindrical platen frame secured against rotation, of a cushioned striking or platen strip forming part thereof, a plurality of paper-feeding rollers mounted in the platen frame, gears on said rollers, and a master gear meshing with all of the 100 gears on said rollers for simultaneously actuating said rollers.

5. In a typewriter platen, the combination with a skeleton cylindrical platen frame secured against rotation, of a cushioned striking or platen strip forming part thereof, a plurality of paper-feeding rollers mounted in the platen frame, gears on said rollers, and an internal gear meshing with 105 all of the gears on the rollers for simultaneously actuating said rollers.

6. In a typewriter platen, the combination with a skeleton cylindrical platen frame secured against rotation, of a cushioned striking or platen strip forming part thereof, a plurality of paper-feeding rollers mounted in the platen frame, gears on said rollers, a central shaft, a gear on said shaft, meshing with all of the gears on the rollers, and means for rotating said shaft and gear 115 thereon for simultaneously actuating said rollers.

7. In a typewriter platen, the combination with a skeleton cylindrical platen frame secured against rotation, of a cushioned striking or platen strip forming part thereof, a plurality of paper-feeding rollers mounted in the platen frame, gears on said rollers, an internal gear meshing with the 120 gears on the rollers, and means on the pe- 130

riphery of said internal gear for actuating the same.

8. In a typewriter platen, the combination with a skeleton cylindrical casing secured against rotation, of paper-feeding rollers mounted in said casing, a revolute shaft operatively connected to said rollers for ro-
- tating the same, a striking or platen strip also mounted in the casing, and cushioning supports for said strip hung loosely on said 10 shaft.

In testimony whereof I have signed my name to this specification.

WILLIAM REDFORD MULOCK.
